UNITED STATES PATENT OFFICE.

HARRY A. HANNOLD, OF CLARION, PENNSYLVANIA.

IRONING-TABLE.

1,209,150.

Specification of Letters Patent. Patented Dec. 19, 1916.

Application filed April 28, 1916. Serial No. 94,091.

To all whom it may concern:

Be it known that I, HARRY A. HANNOLD, a citizen of the United States, residing at Clarion, in the county of Clarion and State 5 of Pennsylvania, have invented certain new and useful Improvements in Ironing-Tables, of which the following is a specification.

This invention relates to ironing tables, and has for its primary object to provide a 10 table capable of being adjusted to compensate for the statures of various users of the same, which provides a strong, stable, and rigid table surface capable of withstanding the strains and pressures incident to the 15 ironing or pressing of materials with the least liability of the same wobbling or becoming distorted, and which, when not in use, may be folded or collapsed to occupy but small space.

20 A further object of the invention is to provide in connection with an ironing table of the above described character, improved means for attaching to the board itself, rests for supporting an iron or other pressing implement, and which also affords means whereby a sleeve board may be readily attached.

With these objects in view, together with others which will appear as the description 25 proceeds, the invention resides in the novel combination and arrangements of parts all as will be described more fully hereinafter, illustrated in the drawings, and particularly pointed out in the claims.

30 The invention will be best understood by reference to the accompanying drawings, wherein—

Figure 1 is a side elevation of an ironing table constructed in accordance with the invention. Fig. 2 is a top plan view of the device illustrated in the above mentioned figure. Fig. 3 is a view similar to Fig. 1, parts being in section, and the table shown in collapsed or folded position. Fig. 4 is a 45 plan view of the table supporting frame with the board removed. Fig. 5 is an enlarged top plan view of the table supporting block, and Fig. 6 is a similar view of the improved traveler.

50 Referring now more particularly to the drawings, 7 indicates generally the table support, the same comprising a suitable base 8, supported upon legs 9, the latter being in turn supported for ready movement upon 55 casters 10. The base or support 8 comprises preferably a vertically disposed column pro-

vided for the major portion of its length with a circular recess 11 for the reception of a standard 12. The standard 12 is of such transverse dimension as to fit snugly 60 and slidably within the said column, a set screw 13 being arranged in the latter for holding the standard in its various positions of vertical adjustment.

The standard 12 is preferably reduced at 65 its outer end as at 13, the said reduced portion being preferably squared as shown in Fig. 4 of the drawings. A block 14 provided with a squared aperture 15 is arranged to be supported upon the squared 70 portion 13 of the standard end, and projecting from opposite sides of the said block 14 is a pair of spaced lugs or ears 16, for the reception of the inner ends of arms 17 constituting a collapsible bracket. The ears 16 75 may be provided with alined apertures within which a pivot pin 18 may be inserted, the said pivot pin securing the adjacent end of each of the arms 17 to the block 14 in pivotal relation. The outer ends of the 80 arms 17 may be formed to provide transversely disposed rests or supports 19 for the accommodation and support of an ironing board 20. The ironing board in this instance is formed in two sections, the said 85 sections being connected at their adjacent ends by suitable hinges 21 to permit of the folding of one section upon the other. One of the arms 17 of the sectional bracket above described is secured by means of screws or 90 bolts 22 to one of the board sections, in order that the same will be carried thereby when the said arm 17 is swung upon its pivot 18, while the opposite arm 17 is adapted merely to releasably support the opposite 95 board section. The board 20 is so related to the sectional bracket that its hinge connection lies directly above the center of the standard 12, and the block 14 may be extended upwardly to terminate even with 100 the outer end of the said standard to afford a suitable central support for the board 20.

Arranged upon the standard 12 for adjustment longitudinally thereof is a traveler 23, the said traveler being provided with 105 oppositely disposed ears or lugs 24 for pivotal connection with links 25, the said links being connected pivotally at their opposite ends with the arms 17 of the sectional bracket, the said connection being effected 110 preferably at a point intermediate the ends of the said arms. A set screw 26 may be ar-

ranged in the traveler 23 to hold the same rigid with the standard 12 in its various positions of adjustment thereon.

In operation, assuming the table to be collapsed, the traveler 23 is forced upwardly of the standard 12, this movement compelling the arms 17 to rock outwardly and upwardly upon their pivots 18 until in substantially horizontal position. The board 10 is then swung to correct position, the free section of the same being moved upon the hinge 21 until it is limited in its movement to be held in horizontal position by the rest 18. The traveler may be held rigid in correct position by operation of the set screw 26. When it is desired to fold the table, the set screw 26 is loosened and the hinged section of the board 20 is swung over upon the opposite section, whereupon the traveler 20 due to the weight of the board and the bracket, will gravitate to the position shown in Fig. 3, and the arms 17 will swing inwardly upon their pivots 18 as is obvious. The entire stand or table may then be rolled 25 upon the casters 10 to any convenient out of the way place.

An iron support or table is indicated at 27; the same being supported upon the board 20 by means of a bracket 28, suitable clips 30 29 being arranged upon the under side of the said table to effect a convenient means for detachably securing the same to the said bracket. It is also apparent that a sleeve 35 board may also be arranged to fit upon the said bracket.

While in the present instance I have shown and described my invention in, what appears to me at this time to be, its most practical form, I do not necessarily restrict 40 myself to the precise construction set forth, but wish it understood that I reserve to myself the right to make such alterations in the minor details of construction and arrangement of parts as I see fit without de- 45 parting from the spirit of the invention.

I claim.

1. In a device of the class described, a standard, a pair of arms one pivoted to project from said standard adjacent one end thereof at opposite points, a board section 50 secured to the free end of one of said arms, a second board section pivoted to said first section, a traveler on said standard, and a connection between said traveler and each of said arms, substantially as described. 55

2. In a device of the class described, a standard, a block secured to one end of said standard, a pair of arms one pivoted at its end to said block to project outwardly therefrom in opposite directions, a rest ar- 60 ranged at the free end of each of said arms, a board rigidly secured to one of said arms to extend substantially parallel therewith, a second board section hingedly connected to said board, a traveler on said standard, and 65 a link connecting each of said arms with said traveler, substantially as described.

3. In a device of the class described, a standard, the said standard being provided with a reduced squared end, a block having 70 a squared aperture arranged over said squared end, an arm pivoted at one end to the opposite sides of said block, a rest formed at the end of each of said arms, a board section rigidly secured to one of said 75 arms, and of such length as to engage at one end upon said squared end and block when said arm is swung outwardly, a second board section pivoted to said end of said first section, a traveler on said standard, and 80 a link connecting each arm intermediate its ends with said traveler, substantially as described.

In testimony whereof I affix my signature in the presence of two witnesses.

HARRY A. HANNOLD.
